UNITED STATES PATENT OFFICE.

JOHN H. MILLS, OF ST. LOUIS, MISSOURI.

HOGSHEAD FOR REDRYING, RECURING, AND RESWEATING TOBACCO.

Application filed November 25, 1921. Serial No. 517,827.

To all whom it may concern:

Be it known that I, JOHN H. MILLS, a citizen of the United States, residing in the city of St. Louis and State of Missouri, have 5 invented certain new and useful Improvements in Hogsheads for Redrying, Recuring, and Sweating Tobacco, of which the following is a specification.

My invention relates to a hogshead for re-drying, recurring and sweating leaf tobacco, and, has for its object to provide a device which is a practical improvement in the art to overcome certain practical objections to, and defects in, the devices at present used 15 for the above purposes.

A further object of the invention is to provide a hogshead to be used in connection with a pump and dry-house and so constructed as to eliminate much of the waste 20 in handling the leaf tobacco.

A further object of the invention is the provision of a hogshead, composed of sections, so constructed and arranged that the same may be quickly opened for removal 25 from the tobacco which is stacked in layers therein, instead of having to remove the tobacco from the hogshead.

A still further object of the invention is to provide the hogshead with an interior 30 perforated separable lining within which the leaf tobacco is packed in layers.

A still further object of the invention is the provision of a plurality of perforated metallic spacer plates for separating the 35 several layers of leaf tobacco packed within the hogshead.

A still further object of the invention is the provision of a hogshead of the class described which is simple and comparatively 40 inexpensive in construction, conveniently assembled and disassembled, easy to handle and highly efficient for the purpose intended.

With the above and other objects in view, 45 the invention consists in the novel features of construction, arrangement and combination of parts hereinafter more fully described and finally pointed out in the claims hereto appended.

50 Referring to the accompanying drawings forming a part of this specification wherein like characters of reference denote similar parts throughout the several views:

Fig. 1, is a view showing a plurality of hogsheads connected with a dry-house and 55 pump.

Fig. 2, is a top plan view of a hogshead.

Fig. 3, is a side elevation of the hogshead.

Fig. 4, is a sectional view taken on line 4—4 of Fig. 2.

Fig. 5, is a sectional view taken on line 5—5 of Fig. 2.

Fig. 6, is a sectional view taken on line 6—6 of Fig. 2.

Fig. 7, is a sectional view taken on line 7—7 of Fig. 2.

Fig. 8, is a plan view in full lines of the hogshead closed with the upper cover removed. The same view shows the hogshead 70 swung open in dotted lines.

Fig. 9, is a plan view of one of the spacers.

Fig. 10, is a side elevation thereof.

Fig. 11, is a detail of one of the lining 75 members.

Fig. 12, is a detail showing the plug and socket attachment for the bottom plate of the hogshead.

In carrying out the aim of my present 80 invention, I employ a hogshead of the class described, which consists of a lower and an upper section, circular in cross section, designated A and B, respectively.

The lower hogshead section A consists 85 of two suitable semi-circular wall members 1 hingedly connected upon one side by means of suitable hinges 2 so that the wall members 1 may be swung open, or closed, like a clam, as is manifest, and clearly 90 shown in Fig. 8. The hinges 2 are preferably secured to the outer face of each wall member 1, although they may be fixed to the inner face of the wall members, if desired, as is manifest.

95 Each wall member 1 of the lower hogshead section A is provided at its upper edge with an upwardly directed flange 3. This flange 3 extends upwardly from the inner surface of the lower hogshead section A, 100 as shown in Figs. 4 to 7, inclusive.

A pair of suitable brackets 4 are each suitably fixed to the inner face of each hinged wall member 1 of the lower hogshead section A, and, they are arranged in pairs 105 diametrically opposite each other when the

wall members 1 are in their closed position. Each bracket 4 is provided with a vertically disposed opening or passage 5.

5 A suitable hinge hasp 6 is fixed at its lower end to the inner face of each wall member 1 of the lower hogshead section A. The hasps 6 are arranged in opposed relation when the wall members 1 are in their closed position.

10 The upper hogshead section B consists of two suitable semi-circular wall members 7 hingedly united upon one side by means of suitable hinges 8. These wall members 7 which comprise the upper walls of the upper hogshead section B may be swung open, or closed, like a clam, the same as the lower hogshead section A. The hinges 8 are preferably, although not necessarily, fixed to the outer face of the wall members 7, of the upper hogshead section B.

15 A pair of suitable lock pins, or arms 9 are suitably fixed to the inner face of each wall member 7 of the upper hogshead section B near the lower edge thereof. These pins 9 are directed downward a suitable distance so that when the upper hogshead section B is placed upon the lower hogshead section A, the pins 9 will be received in the passages 5 of the brackets 4 of the lower hogshead section A, as clearly shown in Figs. 4 to 7, inclusive. This arrangement firmly positions the upper hogshead section B upon the lower hogshead section A, as is manifest. A suitable packing ring 10 is interposed between the lower edge of the upper hogshead section B and the upper edge of the lower hogshead section A to prevent leakage of air from within outward.

20 A pair of suitable brackets 11 are suitably fixed to the inner face of each hinged wall member 7 of the upper hogshead section B near the upper edge thereof, as clearly shown in Figs. 4 to 7. Each hinged wall member 7 of the upper hogshead section B is 25 provided with a staple fastener 12 for passage through an opening in the hasps 6 when the two hogshead sections A and B are in united position. The hasps 6 are prevented from working off of the staple fasteners 12 by means of suitable wire fasteners 13 connected to the staple fasteners.

25 14 indicates a single piece bottom plate which is removably mounted upon the supporting strips 15 of the wall members 1 of the lower hogshead section A. There is one supporting strip 15 fixed to the inner face of each wall member 1 near the lower edge thereof, as shown in Figs. 4 to 7, inclusive. The bottom plate 14 is provided with an outwardly directed socket 16 having a passage 17 which communicates with the interior of the lower hogshead section through the bottom plate 14. 18 indicates a suitable plug having a passage 19. The plug 18 is receivable in the socket 16 and is held therein

30 by means of suitable fasteners or arms 20 which are pivotally connected as at 21 at one end to the lower face of the wall of the socket 16. This arrangement permits the plugs to be removed by merely swinging the arms 20 outwardly, as is manifest.

35 22 indicates a suitable locking bar, which passes vertically through loops formed by means of suitable U-shaped fasteners 23. Two of each fasteners 23 are employed with each hogshead section, as shown in Fig. 6. One fastener is fixed to each wall member of each hogshead section and each fastener is fixed to its respective wall member at one end only, so that the other end of the fastener will remain unfixed to permit free swinging movement of the wall members upon their respective hinges after the bar 22 has been removed from contact with the fasteners 23, as is evident from Figs. 6 and 8.

40 When the walls of the hogshead sections are first closed, they are locked in united relation by means of the hooks 24, which are connected to their respective wall members by means of a staple 25. The free end of each hook 24 is receivable in the hook eye 26 which is fixed to the wall member opposite that to which the hook is connected, as is manifest. The hooks are so arranged that they may be disconnected or disengaged from the eyes 26 by merely forcing the bar 22 downwardly between the fasteners 23 and the walls of the hogshead, as is manifest. The bar 22 insures a positive lock when the hogshead is closed, while the hooks and eyes merely provide an initial or temporary lock when the hogshead is first assembled.

45 After the hogshead has been closed and the bottom 14 placed therein, I provide the hogshead with a suitable separable tubular lining for receiving leaf tobacco in layers and it consists of a lower and upper section, each designated C and C' each composed of two like parts 27 having their upper edge provided with an outwardly directed flange 28. The flange 28 of the lower section C is supported by the brackets 4 of the lower hogshead section A, and the flange 28 of the upper section C' is supported by the bracket 11 of the upper hogshead section B. The wall of each member 27 constituting the lining is provided with a plurality of openings 29 to permit of a free circulation of air, etc., between the interior of the lining or packed leaf tobacco container and the annular chamber D between the lining and the wall of the hogshead proper, as clearly shown in Fig. 7. Two of the lining members 27 have the flange 28 provided with a recess 27' for the passage of the locking bar 22 when the hogshead is assembled.

50 The top of the hogshead is removable and separable. It consists of two parts, or head members 30. Fixed to each head member 30 near its straight edge is a U-shaped strap

member or keeper 31. A suitable locking member 32 is receivable between the keepers 31 and the upper surface of the head members to prevent removal of the upper head 5 until the locking member 32 is withdrawn, as is manifest. The upper head members 30 lie upon the flange 28 of the upper lining section C' and is prevented from casual upward movement by the strips 33 which are 10 fixed to the inner face of the wall member 7 of the upper hogshead section B near the upper edge thereof. One of the upper head members 30 is provided with a socket 34 adapted to receive a suitable 15 plug 35 having the stem 36. The plug and stem are provided with a passage 37 which communicates with a passage 38 of the head member provided with the socket.

The spacer plates E, one of which is positioned between each two layers of leaf tobacco when packing same, as shown in Fig. 7, consists of two circular suitable plates 38 which are spaced apart by means of a plurality of suitable strips 39 so as to provide 25 passages 40 between the plates 38. The plates 38 are provided with a plurality of openings 41 as shown in Fig. 9. The passages 40 and openings 41 permit a free circulation between and through the tobacco 30 spacer plates, as is manifest. The top plate is provided with a hinged arm 41' to facilitate laying and removing the spacers. The arms lie flat upon the plate when between layers of leaf tobacco. The plates are united 35 by suitable means.

The operation of the device is as follows: The lower hogshead section is first closed and hooked after the bottom plate 14 is positioned upon the strip 15. Then the 40 lower lining section C is positioned within the lower hogshead section A and supported by the brackets 4. After the lower hogshead section A has been assembled, the upper hogshead section B may be mounted upon 45 the lower section A after it has been closed and locked by means of the hooks and eyes. It is, of course, understood that the upper section is held united with the lower section and against displacement by means of the locking pins 9 passing through the openings 5 of the brackets 4 and by means of the hasp fasteners 6. After the upper hogshead section B has been properly mounted upon the lower section A, the upper lining 55 section C' of two parts is positioned and supported by means of the brackets 11, as is manifest.

One may start to lay or pack the leaf tobacco in layers, designated F, as shown 60 in Fig. 7, before or after the upper hogshead section B has been assembled and mounted upon the lower section A, as desired. After the leaf tobacco has been packed in layers F and spaced apart by 65 means of the spacers E, the lid or upper

cover is positioned and then one or more of the hogsheads are connected with the dry-house. The first hogshead, as shown in Fig. 1, is suitably connected with a dry-house 42 by means of the pipe connection 70 43. The pipe leads from the upper part of the interior of the house 42 to the plug 18 of the first hogshead. The second hogshead is connected with the first hogshead by means of a suitable tube or pipe connection 75 44 having connection at each end with the stems 36 of the plugs 35. The third hogshead is connected with the second hogshead by means of a suitable tube or pipe connection 45 which is connected at each end to the plugs 18 carried 80 in the sockets 16 of the bottom plate 14 of the hogsheads.

The dry-house 42 is provided with steam pipes 46 for heating the air in the dry-house that is to be used in circulating the 85 hogsheads.

47 indicates a suitable pump for drawing the air from the dry-house and forcing it into circulation through the interior of the 90 hogsheads filled with layers of leaf tobacco.

After the tobacco has been recured, re-dried or resweated, the tube or pipe connections are removed, and, the upper head 95 is then removed. After the upper head is removed from the hogshead, the locking bar 22 is removed or withdrawn from its keepers 23 and then the lower and upper hogshead sections are both swung clear of 100 the packed tobacco and the lining sections C and C' which surround the tobacco, as shown in Fig. 8. After the hogshead has been opened in this manner, the same may be pushed clear of the pile of tobacco so 105 that the lining sections C and C' may be removed and then the layers of tobacco can be easily removed, as access can be readily had without having to get into the hogshead.

Regardless of whether dry air, steam or fluid is pumped through the hogsheads, it will be observed that they are free to circulate due to the perforated lining sections, the chamber D and the perforated and 110 spaced plates E.

The many advantages of the herein described invention will readily suggest themselves to those skilled in the art to which it appertains.

I do not wish to be understood as having limited myself to the details of construction shown and described, but desire to have it understood that the invention I have shown in the drawings is merely illustrative, as it is manifest that various minor changes may be made in the exact construction and particular arrangement of parts without departing from the spirit of my invention, hence I reserve the right to make any such 120 changes, or modifications as may fairly fall 125 130

within the scope of the appended claims when fairly construed.

What I claim is:

1. A hogshead for redrying, recurring and resweating leaf tobacco comprising a lower hogshead section consisting of two halves hingedly united on one side, an upper hogshead section consisting of two halves hingedly united on one side, a separable 10 perforated tubular lining disposed within the hogshead sections for receiving leaf tobacco to be packed in layers, a perforated spacer between each layer of tobacco, a bottom for the hogshead, a top therefor and 15 means for locking the hogshead in its closed position when treating the tobacco packed therein. 75
2. A hogshead for redrying, recurring and resweating leaf tobacco comprising two 20 hinged sections, a separable perforated lining for each section spaced from the walls of the hogshead sections, means for supporting and holding the lining from displacement within the hogshead, a removable bottom plate, a separable upper 25 plate and means for locking the hinged sections together. 80
3. A hogshead for redrying, recurring and resweating leaf tobacco, comprising a lower 30 two piece hingedly united hogshead section, an upper two-piece hingedly united hogshead section removably mounted upon said lower hogshead section, means to prevent lateral displacement of the upper hogshead 35 section upon the lower hogshead section, means for locking the upper and lower hogshead sections together, means for locking the upper and lower hogshead sections in their closed position, a removable bottom plate for 40 said lower hogshead section, a removable and separable upper plate for said upper hogshead section, a perforated tubular separable lining mounted concentrically within the hogshead sections and spaced from the walls 45 of the hogshead sections to form a circulating chamber around the perforated lining, said lining providing an interior chamber adapted to be filled with leaf tobacco deposited in layers and means for spacing the 50 layers of tobacco apart so as to permit air, steam, or liquid to freely circulate between the layers of tobacco and the annular circulating chamber surrounding the lining, and means for creating a forced circulation 55 of air, steam or liquid through one or more hogsheads at a time. 100
4. A hogshead for redrying, recurring and resweating leaf tobacco, consisting of a lower section and an upper section, each consisting of two semicircular halves, a removable bottom for the lower section, a two-piece separable top plate for the upper section, a tubular two-piece separable lining for each hogshead section, means for supporting the lining concentrically within 60 each section to form an annular circulating chamber between the walls of the hogshead sections and the lining sections, said lining sections being perforated to establish communication between the interior tobacco receiving chamber of the lining and the annular circulating chamber, spacer plates to be arranged between adjacent layers of leaf tobacco deposited in the tobacco receiving chamber of the lining to permit of a general circulation between the several layers of tobacco being redried, recured or resweated, means for locking the several parts of the hogshead together when in use and means for spreading the hogshead sections together for removing the hogshead sections from the lining and the tobacco therein, thus eliminating the manual removal of the tobacco from the hogshead. 115
5. A hogshead for redrying, recurring and resweating leaf tobacco comprising, in combination, a lower hogshead section and an upper hogshead section each section consisting of two halves hingedly united so they can be opened and closed, a two piece separable lining mounted within each hogshead section to form a tobacco receiving chamber, an annular circulating chamber formed between the lining and the walls of the hogshead sections, a bottom for said lower section, a top for said upper section, said lining being perforated to establish communication between the annular chamber and the tobacco receiving chamber of the lining, means permitting the egress of air, steam or fluid into the hogshead and means permitting the exit thereof after having circulated within the hogshead. 120
6. A hogshead for redrying, recurring and resweating leaf tobacco comprising a lower two piece hingedly united section, an upper two piece hingedly united section, a separable perforated lining mounted within hogshead sections to form an annular circulating chamber around the lining which is adapted to receive tobacco in spaced layers for redrying, recurring and resweating, means for closing the ends of the hogshead, means for locking the lower and upper sections together and means for locking each section together when in use. 125
7. In a leaf tobacco treating structure, a separable tubular body, a removable bottom for said body, a separable tubular inner lining disposed within said body and spaced from the wall thereof, said lining having its wall provided with a multiplicity of openings, perforated spacers disposed within the tubular lining sandwiching layers of leaf tobacco therebetween and a top closure for said structure. 130
8. In a leaf tobacco treating structure, a hogshead consisting of a sectional hinged tubular section, means for uniting said sections, a removable bottom for the lower sec- 135

tion having a dry air inlet opening, a sectional separable lining having its walls provided with a multiplicity of openings, said lining being centrally disposed within the 5 hogshead, means for retaining the lining in position within the hogshead, a plurality of perforated spacer plates disposed within

the perforated lining between layers of leaf tobacco disposed therein and a separable top closure for said hogshead having an air 10 outlet therein.

In testimony whereof, I have hereunto signed my name to the specification.

JOHN H. MILLS.
